United States Patent Office

Des. 189,031

Patented Oct. 18, 1960

189,031

TILE

Donald E. Allen, Westview, Ohio, assignor to Summitville Tiles, Inc., Summitville, Ohio, a corporation of Ohio

Filed Apr. 29, 1959, Ser. No. 55,701

Term of patent 14 years

(Cl. D18—2)

FIG. 1

—2

FIG. 2

Fig. 1 is a front perspective view of a tile showing my new design; and

Fig. 2 is a cross sectional view taken substantially as indicated on line 2—2 in Fig. 1.

I claim:

The ornamental design for a tile, substantially as shown.
